CLAIM

The ornamental design for a shoe upper, as shown and described.

DESCRIPTION

FIG. 1 is a first rear perspective view of a shoe upper showing my new design;

FIG. 2 is a rear view thereof; and,

FIG. 3 is a second rear perspective view thereof.

The even-length broken line showing in a rectangular shape represents stitching. The broken lines showing the remainder of the shoe are for environmental purposes only and form no part of the claimed design.
